CLAIM

The ornamental design for a protective wall rail, as
shown and described.

DESCRIPTION

FIG. 1 is a top perspective view of a first embodiment
of a protective wall rail, showing my new design, the
midportion thereof being broken away for clarity of
illustration;

FIG. 2 is an end view thereof;

FIG. 3 is a bottom plan view thereof, the midportion
thereof again being broken away;

FIGS. 4-6 are views similar to FIGS. 1-3, respectively,
but showing a modified form thereof.

Both embodiments of the design are in the form of strips
of indeterminate length.
